[57] CLAIM

The ornamental design for a side element of a shoe, as
shown and described.

DESCRIPTION

FIG. 1 is a perspective view of a side element of a shoe
showing my new design;

FIG. 2 is a side elevational view thereof;

FIG. 3 is a front elevational view thereof; and,

FIG. 4 is a top plan view thereof.

The broken line showing of the eyelets, the stitching at the
upper edge of the side element of the shoe and remainder of
the shoe is for illustrative purposes and forms no part of the
claimed design.
